TELEPHONE PAY STATION APPARATUS

George A. Long, Hartford, Conn., assignor to The
Gray Telephone Pay Station Company, Hart-
ford, Conn., a corporation of Connecticut

Application April 4, 1933, Serial No. 664,381

8 Claims. (Cl. 116—149)

My invention relates to apparatus employed in connection with telephones to denote payment for use of the instruments, and an object of my invention, among others, is to so improve the sounding devices that the sounds will not be unduly prolonged.

One form of a structure embodying my invention and in the construction and use of which the objects herein set out, as well as others, may be attained is illustrated in the accompanying drawing, in which—

Figure 1 shows the interior of the coin channel box of a telephone, a portion of the channel plate therein being shown with a single coin channel.

Figure 2 is a side view of said box broken away and showing the coin channel plate in edge view.

Figure 3 is a detail view on enlarged scale illustrating the construction of my improved damper.

Figure 4 is a similar view but looking in a different direction from the point of view of Figure 3.

Figure 5 is a view in section on a plane denoted by the dotted line 4—4 of Figure 3.

In telephone apparatus now in common use prepayment for use of the instrument is denoted by sound devices, such as bells, gongs, and the like, the coins in their passage along the channels in a coin channel plate striking the sounding devices and the sounds being conveyed over the circuit to apprise the central office of the prepayment of the fee. An objection exists in such apparatus in that the sounds of the devices are unnecessarily prolonged so that conversation, if immediately begun, is indistinct and this necessitates a wait to permit the sounds of the devices to subside, thereby curtailing valuable time during which conversation may be carried on. Further than this, signals having prolonged sounds if struck first commingle with other signals causing such signals to become indistinct and thereby confusing the operator as to which signals have been sounded to denote the deposit of certain coins, it being observed that the order of the deposit of a number of coins is determined by the user of the telephone instrument. This applies particularly to gongs which are commonly employed in the apparatus.

Various means have been attempted to overcome this objection but in such cases the tone of the signal is changed and this is not desired. By the use of my improved device it is possible to shorten to any desired degree the length of time during which the sounds from a certain bell or gong will continue and at the same time maintain the tone of such sounding device, such im-

provement being illustrated in the accompanying drawing in which the numeral 7 denotes a portion of a channel plate commonly used in connection with telephone pay stations, such plate having a number of coin channels to direct coins or other prepayment devices to the signals.

The term "coin" as used throughout this specification will be understood to denote any element or device, as tokens or the like, which are lawfully employed for prepayment purposes.

The plate 7 is supported in a box 8 in which apparatus actuated by the coin and for disposition thereof is contained, this box being of any usual construction. The channels 9 provide devious paths for coins 10 which are inserted in slots in the top of the box at the mouth of each channel in a manner that will be readily understood. The coin 10 in its travel along the path, in the structure herein shown, strikes a gong 11 commonly formed from resonant material helically disposed, and as shown in Fig. 2 of the drawing.

It is this form of a gong that has heretofore caused the trouble herein explained. In carrying out my purpose a bar 12 is secured to the side of the box 8, said bar having a dove-tail shaped rib 13 to be received in a groove of similar shape in a hub 14. The shank 15 of the gong 11 is inserted in a hole in the hub 14 and is secured rigidly therein. I also provide a damper which is pressed against the shank of the gong to reduce the vibration, means being provided for varying the pressure of the damper against the shank of the gong whereby pressures of various degrees may be exerted. The damper is preferably composed of a comparatively soft substance such as will absorb the vibrations to a greater or lesser extent.

I have in mind various ways for accomplishing my purpose, that herein shown having proved satisfactory. This damper comprises a finger 16 having a stem 17 which is inserted in a hole in the hub 14, the stem somewhat tightly fitting the hole but to an extent to enable it to be turned to press the finger against the shank 15, the friction of the stem in the hole, however, being sufficient to hold the finger in any position in which it may be placed to exert pressure against the shank 15. This finger is preferably composed of aluminum.

The damper in fact includes the hub 14 which may be removably secured in place as by means of a screw bolt 18. The gong shank is secured in place in the hub, the fingers placed in position and then by means of pliers or otherwise the

pressure of each finger 16 against the shank of the gong is graduated until the desired length of time of vibration is obtained. The dampers may thus be manufactured in quantities and may be "tuned" to the desired degree to be placed in position as may be required.

I claim:

1. In combination in a telephone, a gong having a stem, a support in which said stem is secured, a damper positioned for contact with said gong, and means to maintain a variable degree of contact of said damper with said gong.

2. In combination in a telephone, a gong having a stem, a support in which said stem is secured, a damper positioned for contact with said stem, and means to maintain a variable degree of pressure of said damper against said stem.

3. In combination in a telephone, a gong having a stem, a support in which said stem is secured, a damper composed of comparatively soft metal positioned for contact with said stem, and means to maintain a variable degree of pressure of said damper against said stem.

4. In combination in a telephone, a gong having a stem, a support in which said stem is secured, a damper frictionally held in a hole in said support and having a projection positioned to contact with said stem, the friction of the damper in said hole being sufficient to maintain any required pressure of the projection against said stem.

5. In combination in a telephone, a support, means for fastening said support in place in said telephone, a sounding device secured to said support, means for clamping the support within the telephone case, a damper secured to said support and positioned for contact with said sounding device, said damper being adjustably mounted relative to said clamping means to exert a va-

riable pressure against said sounding device and means to maintain a variable degree of pressure of said damper against said sounding device.

6. In combination in a telephone, a support means for fastening said support in place in said telephone, a gong having a stem secured to said support, means for clamping the support within the telephone case, a damper secured to said support and positioned for contact with said gong, said damper being adjustably mounted relative to said clamping means to exert a variable pressure against said gong, and means to maintain a variable degree of contact of said damper with said gong.

7. In combination in a telephone, a support, means for fastening said support in place in said telephone, a gong having a stem secured to said support, means for clamping the support within the telephone case, a damper attached to said support and positioned for contact with said stem, said damper being adjustably mounted relative to said clamping means to exert a variable pressure against said gong and means to maintain a variable degree of pressure of said damper against said stem.

8. In combination in a telephone, a support, means for fastening said support in place in said telephone, a gong having a stem secured to said support, means for clamping the support within the telephone case, a damper secured to said support and composed of comparatively soft metal, said damper being positioned for contact with said stem, said damper being adjustably mounted relative to said clamping means to exert a variable pressure against said gong and means to maintain a variable degree of pressure of said damper against said stem.

GEORGE A. LONG.
